UNITED STATES PATENT OFFICE

158,945

GAUGE

Walter K. Dow, Longmeadow, Mass.

Application January 5, 1949, Serial No. 65

Term of patent 7 years

(Cl. D52—1)

To all whom it may concern:

Be it known that I, Walter K. Dow, a citizen of the United States and resident of Longmeadow, in the county of Hampden and State of Massachusetts, have invented a new, original, and ornamental Design for a Gauge, of which the following is a specification, reference being had to the accompanying drawings, forming part thereof.

Fig. 1 is a front elevational view of a gauge, showing my new design;

Fig. 2 is a side view of the device shown in Fig. 1.

I claim:

The ornamental design for a gauge, substantially as shown.

WALTER K. DOW.
